UNITED STATES PATENT OFFICE.

ANDREW L. BRITTON, OF PHILADELPHIA, PENNSYLVANIA.

EAR-MUFF.

SPECIFICATION forming part of Letters Patent No. 352,032, dated November 2, 1886.

Application filed April 13, 1886. Serial No. 198,664. (No model.)

To all whom it may concern:

Be it known that I, ANDREW L. BRITTON, a citizen of the United States, residing in the city and county of Philadelphia, State of Pennsylvania, have invented a new and useful Improvement in Ear-Muffs, which improvement is fully set forth in the following specification and accompanying drawings, in which—

Figure 1 represents a side elevation of a frame for an ear-muff embodying my invention. Fig. 2 represents a top or plan view thereof. Fig. 3 represents a section of a portion thereof in line $x x$, Fig. 2, on an enlarged scale.

Similar letters of reference indicate corresponding parts in the several figures.

My invention consists of a novel means for connecting the frames of the ear-pieces with the head-piece, the same being of simple and inexpensive construction, as will be hereinafter fully set forth.

Referring to the drawings, A represents the frames of the ear-pieces of an ear-muff, and B represents the head-piece thereof, the several pieces being formed of wire.

Connected with frames A are ears C, and

formed on the head-piece, near the ends thereof, are shoulders D. The ends of the head-piece are passed through the ears C and the extreme ends hammered, forming heads, which, in connection with the shoulders D, secure the frames A to the piece B and retain said frames in position, the ends of the head-piece forming journals, on which the ear-pieces may turn, in order to conform to the sides of the head of the wearer and set nicely in position, it being evident that the means employed for connecting the ear-pieces with the head-piece are simple and inexpensive.

Having thus described my invention, what I claim as new, and desire to secure by Letters Patent, is—

In an ear-muff, the frame A, having a single ear, C, attached to the frame thereof, in combination with the head-piece B, having shoulder D, the end of said piece B passing through the ear C and headed, substantially as and for the purpose described.

A. L. BRITTON.
